CLAIM

The ornamental design for an electronic device, as shown and described.

DESCRIPTION

FIG. 1 is a front perspective view of an electronic device showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of a portion of the electronic device taken from FIG. 2.

The dot-dashed broken lines in the Figures are for the purpose of illustrating from where the enlarged views are taken and form no part of the claimed design.

The dashed broken lines in the Figures show portions of the electronic device that form no part of the claimed design.
